The ornamental design for a wall sconce frame, as shown and described.

DESCRIPTION

FIG. 1 is a front elevational view of wall sconce frame showing my new design;

FIG. 2 is a side elevational view thereof, opposite side being identical; and,

FIG. 3 is a bottom plan view thereof.

The broken-line showing of environmental structures in FIGS. 1-3 is for illustrative purposes only and forms no part of the claimed design.
